G. A. HUBER

ELECTRIC BELL

Filed June 7, 1922

INVENTOR
Gustav Adolph Huber
BY
A. Ade Bonneville

ATTORNEY

UNITED STATES PATENT OFFICE.

GUSTAV ADOLPH HUBER, OF LANDING, NEW JERSEY.

ELECTRIC BELL.

Application filed June 7, 1922. Serial No. 566,623.

To all whom it may concern:

Be it known that I, GUSTAV ADOLPH HUBER, a citizen of the United States, and resident of Landing, in the county of Morris and State of New Jersey, have invented certain new and useful Improvements in an Electric Bell, of which the following is a specification.

This invention relates to an electric bell. 10 Its object is the production of a bell that is composed of but few parts, and which is provided with a clapper that can be rapidly reciprocated to strike a gong. A second object of the invention is the production of 15 an electric bell provided with a gong, that covers the movable elements thereof to protect them.

Other objects will be evident from the following description and claims.

20 Fig. 1 represents a front view of the electric bell with the gong thereof removed; Fig. 2 shows a rear view of Fig. 1; Fig. 3 indicates a top plan view of Fig. 1, with the gong thereof in axial horizontal section; Fig. 25 4 represents a left hand side view of Fig. 1 with the gong thereof in vertical axial section; Fig. 5 shows a left hand side view of Fig. 1 with the gong thereof in vertical axial section; Fig. 6 represents an elevation 30 of an armature; Fig. 7 is a top plan view of Fig. 6; Fig. 8 shows a left hand side view of Fig. 6 and Fig. 9 shows the bell with a wiring diagram.

A frame is indicated in its entirety by the 35 letter A and comprises the front wall 20, from which rearwardly extends the flange 21. The wall 20 has formed therein the central longitudinal opening 22, and in this instance has pressed out therefrom the outwardly extending guide lug 23 forming the opening 24 in the wall 20.

A guide lug 28 with the guide opening 29, is also pressed out from the wall 20, leaving the opening 30 therein.

45 An angle shaped bracket 33 of non-magnetic material with the foot 34, extends from the wall 20, and the foot 34 of said bracket bears against the inner face of the wall 20, and is fastened thereto by the screw 35. A 50 second angle shaped bracket 36 of non-magnetic material is indicated with the foot 37. The latter foot bears against the inner face of the wall 20 and is fastened thereto by the screw 38. An opening 39 is also formed in the wall 20, to secure the frame in place.

A guide flange 40 is formed in the wall 20 having an opening 41 therein.

An electro-magnet 42 is indicated with its core 43, and the latter is supported in the brackets 33 and 36. A pair of binding posts 45 and 50 extend from the wall 20. A contact post 51 is indicated with the contact piece 52 and the foot 53. The post 51 is fastened to the wall 20, by means of the screw 54, and washers 55 and 56 insulate the foot 53 from the wall 20.

A wire 60 leads from one end of the winding of the electro-magnet 42 to contact post 51. A wire 62 leads from the other end of said winding to the binding post 50.

70 A reciprocating armature is indicated in its entirety by the letter B and comprises the U shaped body portion 64 with the clapper 65 and of non-magnetic material, in this instance German silver. The open end of the 75 U shaped portions has soldered thereto the U shaped member C of magnetic material, in this instance of soft iron, with the guide lugs 66, arms with the upturned ends 67 and the lug 68 perpendicular to the plane of the 80 body portion 64.

The armature B is spaced from the frame 20 and adapted to slide on the flange 40 and the clapper 65 thereof through the lug 28.

85 A resilient arm D is bifurcated at its upper portion to form the bearing member 72, and the spring contact member 73, with the contact piece 74. A leg 75 of the arm D is fastened to the bracket 36.

A knee shaped bracket 78 with the foot 79 and table 80 is fastened to the wall 20, by means of the screw 81. A gong 82 is supported on the table 80 by means of the screw 83 and covers the armature B.

90 A wire 84 has one end fastened to the binding post 45 and its other end is connected to a source of electric current 85. A wire 86 has one end connected to the source of electric current and its other end is connected to the switch 87, and a wire 88 connects the switch 87 and the binding post 50.

95 To operate the bell, the switch 87 is closed, and an electric current flows through the electro-magnet and magnetizes the core 43, by virtue of which the turned up ends 100 67 of the armature B are moved in the direction of the arrow F, and the clapper 65 strikes the gong 82. When the turned up ends 67 are brought close to the core 43, contact is broken between the contact 105 110

pieces 52 and 74, by reason of the lug 68 of the armature B bearing on the arm D, and the electric current is thereby interrupted. Immediately thereafter the tension of the resilient arm D forces the lug 68 with the armature B in a direction opposite to the arrow F, and the contact pieces 52 and 74 again come in contact and the electric circuit is again closed, whereby the 10 clapper 65 again strikes the gong 82 and the same cycle is repeated. By this means the clapper 65 continuously strikes the gong 82 when the electric circuit is closed.

Various modifications may be made in the 15 invention and this exemplification thereof is to be taken as illustrative and not limitative thereof.

Having described my invention what I 20 desire to secure by Letters Patent and claim is:

1. In an electric bell the combination of a frame, an electro-magnet supported on the frame and spaced therefrom and magnetically insulated from said frame, an armature member with a clapper, slidably supported on the frame, a U shaped member with upturned ends of one piece of magnetic material carried by the armature member, said upturned ends coacting with the core of the 30 electro-magnet to be attracted thereby and means to move the armature member away from said core.

2. In an electric bell the combination of a frame, a pair of brackets of non-magnetic 35 material extending from the frame, an electro-magnet fashioned to one of said pair of brackets, the core of said magnet extending beyond the ends of the coil thereof, an armature member with a body portion 40 of non-magnetic material and having a clapper slidably supported adjacent to the electro-magnet, a U shaped member with upturned ends of one piece of magnetic material extending from the body portion 45 of the armature member, said upturned ends coacting with the core of the electro-magnet to be attracted thereby, a gong in the path of the clapper and a resilient arm with one end fastened to the second of said pair of brackets of non-magnetic 50 material that extend from the frame, a portion of said arm always in contact with said armature member and its swinging end in normal contacting engagement with a 55 stationary contact whereby when the armature member is moved toward the core of said magnet that extends outside of the coil thereof, the contact between the swinging

end of said resilient arm, and said stationary contact current is broken, the tension 60 of said resilient arm moving the armature member to its original position.

3. In an electric bell the combination of a frame, an electro-magnet carried by the frame, the ends of the core of said magnet 65 extending beyond the ends of the coil thereof, an armature member with the body portion thereof of non-magnetic material and having a clapper, slidably supported between the frame and the electro-magnet, a 70 U shaped member with upturned ends of one piece of magnetic material carried by the armature member, said upturned ends coacting with the core of the electro-magnet to be attracted thereby, a lug extending from the frame of said armature member, a guide bracket extending from the frame for said armature member, a contact post with a contact piece extending from the frame, a bracket of non-magnetic material extending 80 from the frame, a resilient arm with one end fastened to the bracket, a portion of the arm in permanent contact with said lug and a contact piece on the swinging end of the resilient arm in the path of the contact piece of the contact post.

4. In an electric bell the combination of a frame, an electro-magnet carried by the frame, the core of the electro-magnet extending beyond the ends of the coil thereof, an armature member with the body portion thereof of non-magnetic material and having a clapper, slidably supported between the frame and the electro-magnet, a U shaped member with upturned ends of one 95 piece of magnetic material carried by the armature member, said upturned ends coacting with the core of the electro-magnet to be attracted thereby, a lug extending from the armature member, a contact post extending from the frame and electrically insulated therefrom, a bracket of non-magnetic material extending from the frame, a resilient arm with one end fastened to the bracket, a portion of said arm in contact with said lug of the armature member, the swinging end of the resilient arm in the path of the contact post, a gong enclosing the armature member and in the path of said clapper and a source of electric current for the electro-magnet.

Signed at Dover, in the county of Morris and State of New Jersey, this 3rd day of June, A. D. 1922.

GUSTAV ADOLPH HUBER.
